GENERATOR FOR HYDROCARBON BURNERS

Roberto Martiri, Buenos Aires, Argentina

Application June 19, 1945, Serial No. 600,358
In Argentina April 25, 1945

2 Claims. (Cl. 158—63)

1

The present invention relates to gas generators for gasifying hydrocarbon fuels for cookers, stoves and other heaters, and has for its object to provide a conditioning base having such characteristics in regard to the generation of gas from liquid fuels, that the carrying into practice thereof implies a considerable advance in the art by simplification of the said process.

Hitherto, different types of gas generators have been used amongst which the most usual ones are those known as the tubular type, formed by a pipe of constant cross section, which on one end receives the pipe feeding the liquid fuel, whereas on the other end it has a branch for the outward passage of the gas generated in the hollow of the chamber.

As is well known, the chambers of tubular generators are of such cross section and capacity that a high degree of heat is required for evaporation to take place therewithin, so much so that permanent burners must be of a certain size so as to obtain a relatively powerful heating effect and consequently the required supply is such that the consumption of gas is excessive in relation to the production. For this reason the efficiency is considerably reduced and other disadvantages are found which detract considerably from the value of the system of auto-generation.

In fact, excessive heating of the generator chamber is applicable only to devices working at high pressures, and the constant re-heating thereof gives rise to troubles with the generation of gas itself, since a certain range of hydrocarbons is burnt, thus considerably reducing the carburation value of the fuel by reason of the impoverishment of its composition.

Moreover, as a consequence of the re-heating, and of the process of constant evaporation in a closed receptacle, which is formed by the chamber, a distillation is caused which has grave consequences in so far as concerns the operation of the device, since the coked or carbonized matter resulting from said process goes on accumulating inside until it chokes and to a large extent nullifies the interior cavity of the chamber.

By means of the present invention these troubles are overcome in an efficient manner, means being provided which avoid a re-heating, so that a rational gasification is achieved in

2

accordance with the demands of the working process.

To this end the present invention comprises essentially a fuel pre-heating chamber which has inlet means for the fuel and is prolonged to form a gasification chamber with an outlet needle valve, and is shaped to provide an extension of the pre-heating body, the gasification and pre-heating chambers being semi-insulated from each other by means of a deep groove formed on the outside of the general body of the pre-heater-gasification device, the last-named device being adapted to be heated by means of a permanent burner supplied from the gasification chamber.

Amongst the objects envisaged by the present invention, an outstanding one is that of being able to operate with an economical auto-gasification since the permanent burner may be supplied with a small fraction of the gas produced in the gasifier, because no more than a small flame is required to condition the fuel in the body of the chamber, heating it sufficiently to gasify the fuel as it passes to the outlet chamber, or jet.

Another object is to enable the generator to be combined with devices having a gravity feed, since in this way with moderate heating high pressures are not produced inside the pre-heating chamber or in the gasifier thus allowing the fuel to enter by means of a simple drop from a small height.

Another object of the invention is to avoid the decomposition of the fuel and to obtain a rich carburetted mixture with the consequent increased efficiency in the heating service.

A further object is to obtain a rational gasification according to the needs of the service without superfluous accumulations and without any carbonization so as to achieve a steady operation without failures or interruptions of any kind.

In order that the invention can be clearly understood and readily carried into effect, I shall describe the same in more detail with reference to the accompanying drawing in which the single figure is a partly sectionized side view of a gas generator according to the invention.

In the drawing the reference letter *a* denotes a liquid fuel pre-heating member, reference letter *b* denotes a gasifier member and reference numeral *c* denotes a burner. The pre-heating member *a* includes a tubular body or sleeve 4 of

metal which forms a preheating chamber 2 for a liquid fuel which is supplied through an inlet pipe 4 from a suitable reservoir (not shown). Body 1 is provided with an outlet opening 13 to supply pre-heated fuel to supplement burners (not shown). Within the chamber 2 is liquid fuel diffusing means 3 in the form of a filling of a metal turnings or other similar filamentary material capable of impeding the flow of the liquid fuel entering the chamber through pipe 4.

The left hand end of tubular body 1 forms a valve seat 5 adapted to be closed by a valve 5' formed on the end of a rod 6. Rod 6 extends through the chamber 2 and is supported on the end of body 1 with a screw thread so as to be adjusted by means of a wheel 7 fixed on the end of the rod.

Screwed into the end of body 1 is the gasifier b which includes a tubular body 0 forming a gasification chamber 8 which is connected through the valve 5—5' to the pre-heating chamber 2. Between the end of body 9 and the bore in the end of member 1 is formed a small semi-gasification chamber 2' which tends to reduce the gasification required of the gasification chamber 8. Within an end portion of the gasification chamber 8 is located a metal diffusion filling 3' similar to filling 3.

The end of body 9 has formed in it a nozzle 10 which forms an outlet jet 10' and to keep this nozzle clean a long obstruction-clearing needle 6' secured to the end of rod 6 is adapted to pass through nozzle 10 when rod 6 is moved to the left.

Body 9 has formed in it a circular groove 11 which leaves only a thin wall portion 9' between the gasification chamber 8 and the pre-heating chamber 2. Due to this the flow of heat from body 9 to body 2 is greatly reduced. The burner c is located below the pre-heating member a and gasifier member b and is fed with gasified fuel through nozzle 10. Burner c is provided with a number of jets for heating the pre-heating chamber and the gasification chamber.

The groove 11 serves to establish an almost complete thermal separation between the pre-heating chamber 2 and the gasification chamber 8 so that they can be heated independently. This difference in heating is brought about by the fact that, while both these members are heated by the same burner, the gasification chamber is of smaller diameter than the pre-heating chamber, i. e. heat radiation surface of the pre-heating member a is materially greater than that of the gasifier member b. Thus the pre-heating chamber is at a lower temperature.

In operation the fuel reaches inlet pipe 4 from a suitable reservoir (not shown) and passes through filling 3, valve 5—5', the semi-gasification chamber 2' and filling 3' to the main gasification chamber 8. The fuel is gasified in chamber 8 and passes in an outlet jet through nozzle 10 to supply burner c.

I claim:

1. A hydrocarbon gas generator for cookers, stoves and other heaters, comprising a pre-heating chamber member for liquid fuel, inlet means for the liquid fuel, an extension to said pre-heating chamber member forming a gasification chamber, said gasification chamber having an extension forming a nozzle and terminating in an outlet jet located adjacent said gasification chamber, said pre-heating and gasification chambers being thermally semi-insulated from each other by means of a deep groove formed

in the said gasification chamber externally of the said pre-heater and gasifier chambers, and a burner located adjacent to and in heat transfer relationship with said pre-heater and gasifier chambers for heating said pre-heater and gasifier chambers, said burner being coupled to said output jet and being permanently fed from said gasification chamber, the pre-heating chamber being of constant cross-section and provided internally with liquid fuel diffusing means, and said gasification chamber being partially filled with liquid fuel diffusing means and is also of constant cross-section and of diameter substantially smaller than the pre-heating chamber, said generator comprising closure means arranged to control the passage of fuel from the pre-heating chamber to the gasification chamber and adjustment means for said control means operable from outside said chambers, the closure means including a valve seat formed and disposed between the pre-heating and gasification chamber, a valve stem slidably disposed in the pre-heating chamber, a valve on said stem adapted to cooperate with the valve seat, and a rod terminating in an obstruction clearing needle disposed coaxially with said stem to form a continuation thereof and slidably arranged within the gasification chamber to pass wholly through the outlet nozzle thereof, said pre-heating chamber having a heat radiation surface materially larger than that of said gasification chamber to maintain the temperature thereof substantially lower than the temperature of the gasification chamber.

2. A hydrocarbon gas generator for cookers, stoves and other heaters, comprising a pre-heating chamber member for liquid fuel, inlet means for the liquid fuel, an extension to said pre-heating chamber member forming a gasification chamber, said gasification chamber having an extension forming a nozzle and terminating in an outlet jet located adjacent said gasification chamber, said pre-heating and gasification chambers being thermally semi-insulated from each other by means of a deep groove formed in the said gasification chamber externally of the said pre-heater and gasifier chambers, and a burner located adjacent to and in heat transfer relationship with said pre-heater and gasifier chambers for heating said pre-heater and gasifier chambers, said burner being coupled to said output jet and being permanently fed from said gasification chamber, the pre-heating chamber being of constant cross-section and provided internally with liquid fuel diffusing means and including inlet and outlet means for liquid fuel, said gasification chamber being partially filled with liquid fuel diffusing means and being also of constant cross-section and of diameter substantially smaller than the pre-heating chamber, said generator comprising closure means arranged to control the passage of fuel from the pre-heating chamber to the gasification chamber and adjustment means for the control means operable from outside said chambers, the closure means including a valve seat formed and disposed between the pre-heating and gasification chambers, a valve stem slidably disposed in the pre-heating chamber, a valve on said stem adapted to cooperate with the valve seat, and a rod terminating in an obstruction clearing needle disposed slidably within the gasification chamber coaxially with the valve stem to form a continuation thereof, and being arranged to pass wholly through the nozzle and jet of the gasification chamber, said pre-heating chamber having a heat radiation surface materially larger

than that of said gasification chamber to maintain the temperature thereof substantially lower than the temperature of the gasification chamber.
